Patented Oct. 15, 1918.

FIG. 1.

UNITED STATES PATENT OFFICE.

ANDREW J. OLIVER, OF CHICAGO, ILLINOIS.

JACK.

1,281,818.

Specification of Letters Patent. Patented Oct. 15, 1918.

Application filed September 12, 1917. Serial No. 190,887.

To all whom it may concern:

Be it known that I, ANDREW J. OLIVER, a citizen of the United States, residing at Chicago, in the county of Cook and State 5 of Illinois, have invented certain new and useful Improvements in Jacks, of which the following is a specification.

The invention relates to lifting jacks of the type comprising a supporting standard, 10 a lifting bar, and lever-actuated mechanism for raising and lowering said bar; and the general object of the invention is to provide a very practical and efficient jack.

A more specific object of the invention is 15 to provide improved raising and lowering mechanism which is of very simple and yet durable construction and the operation of which is easy and positive.

The objects of the invention thus generally stated are attained by the construction and arrangement set forth in the accompanying drawings forming part hereof, in which Figure 1 is a side elevation of the improved jack. Fig. 2 is a top plan view, 25 with parts in section on line 2—2 of Fig. 1. Fig. 3 is a central sectional view on line 3—3 of Fig. 2. Fig. 4 is a fragmental side elevation on an enlarged scale showing a portion of the operating mechanism. Figs. 30 5 and 6 are side elevations, showing the opposite sides, respectively, of the holding member for the rack bar.

The jack comprises a standard 1, a rack bar 2 slidably mounted therein, a pinion 3 meshing with the rack bar, a lever 4 having a spring-controlled actuating member 5 shiftable into and out of operative engagement with said pinion, and a holding member 6 for the rack bar having a pivoted controlling weight 7, said holding member being adapted to be engaged by the member 5 at the end of the upward movement of the lever.

The standard 1, having a supporting base 45 8, is made hollow to receive the rack bar 2 and at its forward edge is enlarged as at 9 to house the actuating mechanism for the rack bar. At its opposite or rearward edge the standard is provided with a vertical slot 10 in which a lifting shoe 11 on the rack bar is adapted to operate; and the upper end of the standard is flanged as at 12 to form a guide for the rack bar 2, which is in the form of an eye beam, and to form 50 55 a stop against which the transverse pin 13 is carried at the lower end of the lifting shoe

is adapted to engage to limit the upward movement of the rack bar.

The rack bar 2 is provided at its rear edge with rack teeth 14 and the pinion 3 meshing with said rack teeth is mounted on a pin 15 carried by the standard.

The operating member 4, which may be provided with a handle 16, is entered through an opening 17 in the rear edge of the standard and is also pivotally mounted on said pin 15 carrying the pinion 3. Said lever is bifurcated at its forward end to receive the actuating member 5 mounted on a pivot pin 18, and a socket 19 is provided in the lever a short distance rearward of the pin 18 to receive a compression spring 20 which is connected to a rearwardly extending arm 21 carried by the actuating member 5. The member 5 has a lower forwardly extending portion or dog 5^a having a notched face 5^c for engagement with the teeth of the pinion 3, and an upper forwardly extending portion or lug 5^b having a pair of cam surfaces 5^d and 5^e formed on its upper side which are adapted to engage with the holding member 6 for the rack bar. The rearwardly extending arm 21 is so positioned with reference to the dog 5^a and lug 5^b that it lies in a plane substantially midway therebetween so that the compression spring 20 holds the member at one side or the other of dead center; and the parts are so proportioned and arranged that when the arm is forced below center, 90 the dog 5^a (which is then held in engagement with the pinion) may escape past a tooth against the action of the spring in the upward movement of the lever without throwing the member to the upper side of 95 dead center.

The holding member 6 for the rack bar is pivoted in the standard 1 above the pinion 3 on a pin 22. Said member is provided with a projecting portion or detent 6^a extending upwardly through an opening 23 in the upper end of the standard and a projecting portion or finger 6^b extending rearwardly through the opening 17 in the rear edge of the standard. The upper end of said detent is provided with a nose 6^c having a rearwardly inclined under surface; and upon one side of said detent above the pin 22 upon which the holding member is mounted, is pivoted the weighted arm 7 for 100 105 110 controlling the position of the member in the operation of the jack. Said arm 7 is

mounted on a pivot pin 7^a on a projection 7^b formed at one side of the detent and a stop 24 is also provided on said projection slightly below the pivot pin 7^a, which stop 5 is arranged to be engaged by the opposite edges of the arm as it is swung downward either forwardly or rearwardly of the pin 22 upon which the holding member is mounted. As the arm engages with said 10 stop, the holding member is rocked thereby to move the detent either in or out of engagement with the rack bar, according to whether the arm is swung forwardly or rearwardly of the pin 22. On the side of 15 said detent opposite the arm 7 is a stop 25 (Figs. 2 and 6), preferably formed integral with the detent and arranged to engage with the wall of the standard at the edge of the opening 23 to limit the forward downward 20 movement of the holding member when the detent is engaged by the rack bar.

The finger 6^b of said controlling member has a cam face 6^c formed on its under surface which is arranged to be engaged by the 25 cam surfaces 5^d and 5^e on the member 5 to actuate the controlling member 6; and the upper surface of said finger engages with the standard of the upper edge of the opening 17 therein and thus also serves to limit 30 the downward forward movement of the detent.

In the operation of the jack, when it is desired to raise the rack bar, the weighted arm 7 on the detent 6^a is swung forwardly in 35 which position it serves to normally hold the detent in engagement with the teeth of the rack bar as shown in Figs. 3 and 4, to permit an upward movement thereof, and to prevent the rack bar from being forced 40 downwardly by a weight on its upper end when the lever 4 is raised into position for a lifting stroke. In this movement of the lever, the actuating member having been shifted in the immediately preceding down- 45 ward movement of the lever in lowering the rack bar to carry the notched face 5^c of the dog into engagement with a tooth of the pinion 3, the rack bar is caused to descend a short distance until the nose of the detent 6^a 50 is carried forwardly by the weighted arm 7 into operative engagement with said rack bar. The pinion 3 is thus locked against movement with the lever 4 by the rack bar and in the further upward movement of said 55 lever it will be seen that the dog 5^a is caused to ride over the upwardly adjacent tooth against the action of the spring 20 and into engagement with said tooth, so that a downward movement of the lever rotates the pinion 60 and elevates the rack bar, the detent 6^a being moved rearwardly by the immediately subjacent tooth of the rack bar engaging with the inclined under surface of the nose of the detent to permit the upward movement of the rack bar. At the end of the 65

downward stroke, the detent is carried forwardly by means of the weighted arm 7 into engagement with the rack bar to hold it against downward movement while the lever is being raised for the next lifting stroke. 70

When it is desired to lower the rack bar, the weighted arm 7 is swung rearwardly into the position shown in broken lines in Fig. 1, in which position the detent 6^a is normally held by the arm out of engagement with the rack bar. Thereupon the lever 4, with the actuating dog in the position shown in Fig. 3, is raised to lower the rack bar. Near the end of its upward movement, the forward cam surface 5^d on the upper side of the lug 5^b engages with the cam-faced finger to actuate the holding member 6 to move the detent forwardly with its nose into engagement with the rack bar and in the further upward movement of 80 the lever the rearward cam surface 5^e of the lug 5^b, engaging with the cam surface 6^c on the finger, shifts the actuating member 5 against the action of the spring 20 to move the dog 5^a out of engagement with the pinion 3. The lever is then lowered and in the downward movement thereof the forward end of the lug 5^b engages with one of the teeth of the pinion 3 to again shift the actuating member 5 so that the dog 5^a engages 85 with the next lower tooth of the pinion, and in the further downward movement of the lever the pinion is actuated to raise the rack bar a short distance, whereupon the detent is released from engagement with the rack 90 bar and is carried into inoperative position by the weighted arm 7. The next upward movement of the lever thus lowers the rack bar until the detent is again moved into engagement therewith by the lug 5^b engaging 95 with the finger 6^b, whereupon the actuating member 5 is shifted as before to clear the pinion during a portion of the downward movement of the lever. 100

I claim as my invention: 110

1. A jack including a standard, a rack bar slidably mounted in said standard, a pinion mounted in the standard and meshing with the rack bar, a holding member for said rack bar with means for limiting its forward movement and means for holding it in or out of engagement with the rack bar, and a lever pivoted in the standard and having an actuating member with means for holding it in or out of operative engagement 115 with the pinion, said actuating member being adapted to engage with the holding member in the upward movement of the lever to move it from inoperative position into engagement with the rack bar and to be 120 moved thereby out of engagement with the pinion. 125

2. A jack including a standard, a rack bar slidably mounted in said standard, a pinion mounted in the standard and mesh- 130

- ing with the rack bar; a holding member for said rack bar having means for limiting its forward movement, means for holding it in or out of engagement therewith and a cam-faced actuating finger, a lever pivoted in the standard, and a spring-controlled actuating member carried by said lever and having a dog adapted to positively engage with said pinion to rotate it in a direction to raise the rack bar and to yieldingly engage with said pinion to rotate it in a direction to lower the rack bar, and a cam-faced lug adapted to engage with the cam-faced actuating finger of the holding member to move said holding member from inoperative position into engagement with the rack bar and to be moved thereby out of engagement with the pinion against the action of its controlling spring.
3. A jack including a standard, a rack bar slidably mounted in said standard, a pinion mounted in the standard and meshing with the rack bar, a holding member for said rack bar with a limited pivotal movement in the standard and having a weighted arm pivoted thereto and adapted to hold it either in or out of operative engagement with said bar, a lever pivoted in the standard, and an actuating member carried by said lever with means for holding it in or out of operative engagement with the pinion, said actuating member being adapted to engage with the holding member in the upward movement of the lever to move it from inoperative position against the action of the weighted arm into engagement with the rack bar and be moved thereby out of engagement with the pinion against the action of its controlling means.
4. A jack including a standard, a rack bar slidably mounted in said standard, a pinion mounted in the standard in mesh with the rack bar, means for actuating the pinion to raise and lower the rack bar, a holding member for the rack bar having a limited pivotal movement, and means for yieldingly holding said holding member in engagement with the rack bar to permit an upward movement thereof and to hold it against downward movement, or for yieldingly holding said member out of engagement with the rack bar to permit a downward movement thereof, the holding member being adapted to be engaged by the pinion-actuating means to be moved thereby into engagement with the rack bar and to move the actuating means out of engagement with the pinion.
5. A jack including a standard, a rack-bar slidably mounted in said standard, a pinion mounted in the standard in mesh with the rack-bar, means for rotating the pinion to raise and lower the rack-bar including a lever, an actuating member movable into and out of engagement with said pinion, and a holding member pivoted in the standard and having controlling means for holding it in or out of engagement with the rack-bar, said pinion-actuating member and said holding member being each adapted to be actuated by engagement with the other when the lever reaches the end of its upward movement in the operation of lowering the rack-bar.
6. A jack including a standard, a rack-bar slidably mounted in said standard, a pinion mounted in the standard in mesh with the rack-bar, means for rotating the pinion to raise and lower the rack-bar including an actuating member movable into and out of engagement with said pinion, and a holding member for the rack-bar having a detent, means for holding the detent in or out of engagement with said rack-bar, and an actuating finger adapted to be engaged by the pinion-actuating member to move the detent from inoperative to operative position and to shift the actuating member out of operative engagement with the pinion in the operation of lowering the rack-bar.
7. A jack including a standard, a rack-bar slidably mounted in said standard, a pinion meshing with the rack-bar, means for actuating the pinion to raise or lower the rack-bar, and a holding member having a pivoted arm adapted to hold said member either in or out of engagement with said rack-bar, said member being adapted in one position of said arm to permit an upward movement of the rack-bar and to hold it against downward movement, and in another position of said arm to permit a downward movement of the rack-bar.
8. In combination with a jack having a standard, a rack bar slidably mounted in said standard, a lever mounted on a fixed pivot in said standard, a pinion, an actuating member yieldingly held either in or out of engagement with said pinion, and a holding member yieldingly held either in or out of engagement with said rack bar, said actuating member and said holding member being adapted to coöperatively engage with the pinion and rack bar respectively in the operation of said lever to effect a raising of the rack bar and with the pinion and rack bar respectively and each other in the operation of said lever to automatically effect a lowering of said rack bar.
9. In combination with a jack, including a standard, a rack-bar slidably mounted in said standard, and a pinion, means for rotating said pinion to raise and lower the rack-bar, including a lever, and a member movably mounted in said lever and adapted to be automatically moved into engagement with the pinion at the beginning of the downward movement of the lever, and to be automatically moved relative to the lever out of engagement with the pinion when the lever is operated to the extreme end of its upward movement, and a holding member

movable into and out of engagement with the rack-bar and coöperating with said actuating member to effect a raising and lowering of the rack-bar.

10. In combination with a jack including a standard, a rack bar slideable in said standard, a lever mounted on a fixed pivot in the standard, a pinion, an actuating member mounted in said lever for movement relative thereto, and a holding member mounted in said standard, said members being adapted

to coöperatively engage with the pinion and rack bar respectively in the operation of said lever to effect a raising of the rack bar and with the pinion and rack bar respectively 15 and each other in the operation of said lever to automatically effect a lowering of said rack bar.

In testimony whereof, I have hereunto set my hand.

ANDREW J. OLIVER.
